UNITED STATES PATENT OFFICE.

EDGAR D. JOHNSTON, OF CONNERSVILLE, INDIANA.

MEANS FOR MOVING SLACK COAL.

SPECIFICATION forming part of Letters Patent No. 449,122, dated March 31, 1891.

Application filed May 24, 1890. Serial No. 352,975. (No model.)

To all whom it may concern:

Be it known that I, EDGAR D. JOHNSTON, a citizen of the United States, and a resident of Connerville, in the county of Fayette and State of Indiana, have invented certain new and useful Improvements in Means for Moving Slack Coal, of which the following is a specification.

The object of my invention is to provide means whereby an air-blast may be utilized to rapidly and economically move slack coal at elevators and mines.

The invention will be first fully described in connection with the accompanying drawings, and will then be particularly referred to, and pointed out in the claim.

Referring to the drawings, in which like parts are indicated by similar reference-letters wherever they occur throughout the various views, Figure 1. is a side elevation of the device with a portion broken away to expose the spiral conveyer. Fig. 2 is a vertical transverse section taken through line $x-x$ of Fig. 1.

Referring to the parts, A represents the conveyer-chamber, and B a spiral conveyer mounted to revolve within it. The central portion of the chamber A is open on top and has flaring sides which terminate in an outwardly-projecting flange a , surrounding the opening, upon which flange is mounted a rectangular metal box or frame C, which forms the base of the hopper. The hopper is formed, preferably, of upright wooden staves C', placed edge to edge with their lower ends within the frame C, to which they are secured by bolts c.

The ends of the conveyer box or chamber A are circular to conform to the conveyer B and having annular flanges a' a^2 to connect with the conveyer-shaft bearing at the driving end and an enlarged chamber E at the opposite end. The blast-pipe F, which is arranged below the conveyer pipe or chamber, is connected to the enlarged chamber by its flanges f, and it has an annular flange f' at its opposite end to connect with a force-blower. (Not shown.) Both the conveyer-pipe and blast-pipe have laterally-projecting flanges a^3 f^3 near their forward ends, which are perforated for fastening-bolts f^3 .

The conveyer-chamber A and blast-pipe F are braced by metal supports G, one upon each side, which are bolted on seats formed

on the pipe and chamber and have outwardly-projecting flanges or feet g at the bottom, which are bolted to the supporting-timbers H of the frame-work. The reduced end of the chamber E has a seat on top of it, upon which the shaft-bearing B' is secured. A packing-gland b surrounds the shaft in the end of the chamber E to prevent dust from entering the bearing. The opposite end of the shaft is also packed for the same purpose. The pipe F should be the same size as the opening to the blower; but the opening from the chamber E tapers smaller toward the point where it connects with the discharge-pipe I.

Coal-slack being fed into the hopper is carried forward by the conveyer and discharged into the chamber E. Here it is met by the blast from the blower, conveyed through pipe F, and forced through the discharge-pipe I to the place of delivery.

I prefer to employ the well-known Roots force-blower to furnish the blast for my apparatus, as I have found by experience that I can with one of his medium-sized blowers attached to my device very rapidly remove slack to a distance of more than one thousand feet and elevate it more than one hundred feet, with the blower speeded to two hundred and fifty to three hundred revolutions per minute and the feed-worm B run at from one-half to two-thirds the speed of the blower; but there are other blowing-engines that may be used to advantage, and it is obvious that many mere mechanical changes in details of construction may be made without departing from the spirit or scope of my invention.

What I claim is—

In a device for moving slack coal, the combination, substantially as hereinbefore set forth, of the conveyer, a hopper mounted thereon to supply said conveyer, an enlarged receiving-chamber connected to the discharge end of the conveyer to receive the slack and having a tapered end to connect to a discharge-pipe, and a blast-pipe leading from a force-blower and connected to the enlarged chamber.

EDGAR D. JOHNSTON.
